PROJECTILE

Wiley T. Moore, United States Army,
Laverne, Okla.

Application January 15, 1941, Serial No. 374,503

3 Claims. (Cl. 102—73)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to projectiles in general, and in particular to small arms explosive or incendiary bullets. In this type of bullet, economy of space and cost of manufacture prohibit the use of the more complicated fuse structures. The present invention deals with a unitary type of firing mechanism having an inertia firing member, which mechanism is safe, simple in nature, low in cost and easy to manufacture and assemble.

It is an object of this invention, therefore, to produce a simplified firing mechanism including primer and striker for incendiary or explosive bullets and the like which mechanism is contained in a single unit for insertion into the bullet.

It is a further object of this invention to produce a self-contained mechanism for small arms and medium projectiles comprising a primer and a striker wherein said striker is a free inertia member.

It is a further object of this invention to produce a self-contained firing mechanism comprising a primer and a striker for small arms and medium projectiles wherein the striker member is an inertia member normally held immobilized by the containing medium.

It is a further object of this invention to produce a self-contained firing mechanism comprising a primer and a striker for small arms and medium projectiles wherein said striker member is an inertia member normally held immobilized by the containing medium.

To these and other ends, the invention consists in the construction, arrangement and combination of elements described hereinafter and pointed out in the claims forming a part of this specification.

A practical embodiment of the invention is illustrated in the accompanying drawing wherein:

Figure 1 is a longitudinal sectional view of a projectile showing the self-contained firing unit in place,

Figures 3 and 5 are similar views of modifications, and

Figures 2, 4 and 6 are longitudinal sectional views of modifications of the firing units.

Referring to the drawing by characters of reference there is shown in Figure 1 a projectile body 1 enclosed by a rifling jacket 2 having a

front portion 3 forming the nose of the bullet. It will be understood that this particular arrangement may be varied in the employment of the invention. For instance, the nose portion 5 may be a part, integral or otherwise, of the body portion as in the usual case, and the projectile may be unjacketed. The nose portion may be so designed as to permit loading from that end.

10 A central bore 6 is provided in the body 1 for explosive or incendiary material or the like.

The nose portion 3 is provided with an axial cavity 9 designed to receive the firing unit. The firing unit consists of a capsule 10 which may 15 be of metal or organic material such as the synthetic resins or both, and part or all of the capsule may be transparent. The capsule of Figure 1 is composed of two telescoped parts and in such case one part may be of metal and the 20 other of plastic, transparent or otherwise. This would afford ready inspection of the interior at any time in storage and prior to loading into the bullet.

As shown in Figure 1, one section of the capsule 25 contains the packed priming material 11 while the inertia member, shown in this instance as a steel sphere 12, is held loosely in the other section. The total mass of the inertia member is so small and the density of 30 packing of the priming material is of such degree that ordinary handling will not detonate the primer. However, at bullet velocities the momentum of even a small mass is of considerable magnitude, and the stoppage of the projectile will serve to fire the primer. The priming material may or may not be covered with a piece 35 of shellacked paper or the like, as in the conventional primers in the cartridge art.

Figure 2 shows a modification of a primer 40 wherein the inertia member 12 is partly embedded in the detonating material 11. This form will increase the safety by restraining the peregrinations of the inertia member prior to firing impact. In all cases, the portion of the 45 capsule containing the inertia member is preferably non-metallic, but it is understood that it may also be metallic, with or without a buffer coating inside to prevent metal to metal contact, such as shellac or the like, if such be desirable.

50 In Figure 3 is shown another form of capsule composed of a single piece 13 although it is understood that this and any other modification of the capsule may be made of separate telescoping pieces if desirable. The inertia member 14 is shown as panduriform in longitudinal sec-

tion and restrained at its recessed portion or waistline by punched-in portion 15 of the capsule 13. The inertia member may be circular in cross section or it may be thinly rectangular or of other shape. In none of the firing units shown, however, is a flash passage necessary as the detonating wave is sufficient to set off the main charge. On the forward part of the member 14 is a protuberance or teat 16 for detonating engagement with the priming 11. The specific form of the inertia member 14 shown is not to be deemed as limiting, since any form of member will lie within the concept of this species of the invention wherein the inertia member has a configuration designed for inter-engagement with the containing capsule. The capsule 13 is shown as crimped at 17 over the firing member 14 to hold the latter in the capsule, but punching 15 may suffice for this purpose and the crimp 17 may be omitted. The punched portion may or may not be sealed off with shellac or other material.

In Figure 4, a firing unit similar to that of Figure 3 is shown, but with the inertia member 14 partially embedded in the priming 11, as in the case of Figure 2.

In Figure 5 a spherical inertia member 12 is contained in a capsule 18 of the general type shown in Figure 3 and is restrained from contacting the priming 11 by an inward dimple 19. The sphere may be held loosely or tightly by the dimple.

In Figure 6 the sphere 12 is shown partly embedded in the priming and with an alternative form of restraining member consisting of a punched portion 20 in the wall of the capsule. The necked portion 21 of the lower part of the capsule in Figure 1 may also be dimpled, punched or otherwise modified to offer a barrier between the inertia member and the priming in ordinary handling, but which will yield on firing impact.

The main problem solved by the projectile of this invention is one of assembly. In prior art explosive bullets, the priming had to be packed into a complete bullet whereas in the present case this loading is performed on a separate capsule and the latter simply placed into the bullet at will. They may thus be stored prior to assembly, and defective loadings are more easily detected, and less expensive and time-consuming consequences ensue therefrom.

I claim:

1. A projectile comprising a main charge and a separate firing component, said firing component comprising an elongated tubular capsule, a detonating charge transversely fixed in the forward end of said capsule, a discrete inertia striker carried in the rear end of said capsule and spaced from said detonating charge, said

capsule providing a substantially free space between said striker and said detonating charge, an inwardly projecting stop member on the wall of said capsule between the rear of said striker and said detonating charge for confining said striker in the rear part of said capsule and out of contact with said detonating charge in ordinary handling and during free flight of the projectile, said stop member being outwardly deformable by pressure of said striker thereagainst during forward movement of said striker upon impact of said projectile with a target to release said striker for further forward movement against said detonating charge.

2. A projectile comprising a main charge and a separate firing component, said firing component comprising an elongated tubular capsule closed at its forward end, a detonating charge transversely fixed in the forward end of said capsule, a discrete inertia striker being a solid of revolution generally panduriform in axial section carried in the rear end of said capsule and spaced from said detonating charge, said capsule providing a substantially free cylindrical space between said striker and said detonating charge, longitudinal fingers continuous with the wall of said capsule engaging the rear portion of said striker confining said striker in the rear part of said capsule and out of contact with said detonating charge in ordinary handling and during free flight of the projectile, said fingers being outwardly deformable by pressure of said striker thereagainst during forward movement of said striker upon impact of said projectile with a target to release said striker for further forward movement against said detonating charge.

3. A projectile comprising a main charge and a separate firing component, said firing component comprising an elongated tubular capsule closed at its forward end, a detonating charge transversely fixed in the forward end of said capsule, a discrete spherical inertia striker carried in the rear end of said capsule and spaced from said detonating charge, said capsule providing a substantially free cylindrical space between said striker and said detonating charge, an inwardly projecting dimple formed in the wall of said capsule between said striker and said detonating charge confining said striker in the rear part of said capsule and out of contact with said detonating charge in ordinary handling and during free flight of the projectile, said dimple being outwardly deformable by pressure of said striker thereagainst during forward movement of said striker upon impact of said projectile with a target to release said striker for further forward movement against said detonating charge.

WILEY T. MOORE.
